No. 789,640.

PATENTED MAY 9, 1905.

J. W. WAINWRIGHT.
JACK FOR ROOFERS, PAINTERS, &c.
APPLICATION FILED MAY 25, 1904.

UNITED STATES PATENT OFFICE.

JOHN W. WAINWRIGHT, OF PHILADELPHIA, PENNSYLVANIA.

JACK FOR ROOFERS, PAINTERS, &c.

SPECIFICATION forming part of Letters Patent No. 789,640, dated May 9, 1905.

Application filed May 25, 1904. Serial No. 209,681.

To all whom it may concern:

Be it known that I, JOHN W. WAINWRIGHT, a citizen of the United States, residing in the city and county of Philadelphia, State of Pennsylvania, have invented a new and useful Improvement in Jacks or Scaffolds for Roofers, Painters, &c., of which the following is a specification.

My invention consists of a jack or scaffold more particularly adapted to be sustained on a metal roof for purposes of roofers, painters, &c., the same being provided with means for automatically clamping or securing it to such roof, more particularly the seam thereof.

It also consists of details of construction, as will be hereinafter described, and pointed out in the claims.

Figure 1 represents a perspective view of a jack embodying my invention. Fig. 2 represents a side elevation of the securing or clamping device employed. Fig. 3 represents a vertical section on line xx , Fig. 1, on an enlarged scale. Fig. 4 represents a vertical section on line yy , Fig. 3.

Similar letters of reference indicate corresponding parts in the figures.

Referring to the drawings, A designates a jack or scaffold for roofers, painters, &c., the same, excepting the feature of my invention applied thereto, being of usual construction.

B designates a pair of jaws whose normal position is open, said jaws being pivoted, as at C, and depending from the toggle D, whereby, as is evident, when said toggle is opened said jaws move toward each other and when said toggle is closed opening motion is imparted to said jaws.

E designates the pivot of the upper levers of the toggle at the top thereof, said pivot being connected with the upright member of the jack, whereby said toggle depends from said member and the jaws B occupy a position at the bottom portion of said member and project somewhat downwardly below the lower end thereof, it being noticed that said jaws point downwardly, so as to open from below, and that the normal positions of the jaws and toggle are as shown in Fig. 2, the opening of the jaws being due to the closed condition of the toggle.

The operation is as follows: The jack is located upon a roof and the jaws in open condition are placed over the seam or groove F thereof, as shown in Fig. 1, it being noticed that the under walls G of the axial portion 55 of the jaws is above said seam or groove. As the jack lowers, due to its weight or gravity, said walls G of the jaws contact with the upper edge of the seam as an abutment, whereby as the toggle is connected by the pivot E with 60 the jack lateral motions are imparted to the levers of the toggle, and so the latter opens, whereby the jaws are moved toward each other or closed and embrace the seam or groove F and are tightly clamped thereupon, 65 the jack thus being interlocked with the seam, and so is controlled against slipping or downward motion. When the jack is to be removed, it is raised, and as the pivot E follows the same the toggle is caused to close, so that 70 the jaws are opened, whereby the latter are removed from the seam and the jack is entirely disconnected from the roof.

Secured to the member F of the jack is the plate H, the same forming a covering for the 75 toggle and preventing the hand of the workman from contacting with the same and adjacent portion of the jaws.

The lower ends of the jaws are inclined, as at J, so as to conform to the pitch or slant of 80 the roof, so that should a seam be of less height said ends will contact with the roof, thus raising the jaws, opening the toggle, and causing said jaws to close upon and clamp 85 said seam, the closing and clamping actions being increased by the downward tendency or weight of the jack imposed upon the pivot E, as in the previous case.

It is evident that when the jack is slightly raised it may be readily moved from the gutter upwardly to the top, or vice versa, and the jaws then engage with the adjacent portion of the seam or groove F, thus locking the jack in position as before.

Various changes may be made in the details 95 of construction shown without departing from the general spirit of my invention, and I do not, therefore, desire to be limited in each case to the same.

Having thus described my invention, what 100

I claim as new, and desire to secure by Letters Patent, is—

1. A roof-jack of the character stated, a pair of movable jaws, levers continuing upwardly from said jaws, and a pivot connecting said levers with said jack, whereby the weight of the jack when located on a roof automatically closes said jaws and the elevation of said jack carries the levers with it and automatically opens said jaws.
  2. A jack, levers pivotally connected therewith, a pair of movable jaws continuous downwardly from said levers, and a pivot connecting said jaws and the lower members of said lever, said lever depending from the jack and said jaws depending from said levers, whereby said jaws are automatically closed by the weight of the jack and automatically opened by the elevation of the same and the ascent of said levers and jaws with the jack.
  3. A roof-jack, a pair of opposed jaws, and levers connected with said jaws and with said jack, said levers depending from said jack, and said jaws depending from said levers and having the under side of their pivotal por-
- tions adapted to abut against an upwardly-projecting member of a roof and automatically close upon the same.
4. A roof-jack of the character stated having self-closing jaws connected therewith and depending therefrom so as to engage a projecting member of the roof.
  5. A roof-jack having jaws adapted to engage with a projecting member of a roof, and a toggle carrying said jaws, said toggle being connectible with a member of the jack.
  6. A roof-jack having a toggle pivoted at its upper end on said jack, and jaws depending from said toggle, said jaws being adapted to clamp a projection of a roof due to the abutment of said jaws with a member of the roof.
  7. A scaffold provided with retaining means adapted to engage the standing seam of a metal roof or the like.

JOHN W. WAINWRIGHT.
